UNITED STATES PATENT OFFICE

ROBERT N. SCHUMANN, OF MADISON, WISCONSIN

CONCRETE RAILROAD TIE

Application filed May 16, 1931. Serial No. 537,910.

This invention relates to concrete railroad ties, and has for one of its objects to provide a tie of this character embodying novel reinforcing means which shall be adapted to prevent the tie from cracking, breaking or crushing under any shocks, jars or loads to which it may be subjected by a passing car or train.

The invention has for a further object to provide a tie of the character stated which shall embody rail plates recessed in the upper surfaces of the end portions of the tie and having anchors embedded in the tie in such manner as to firmly hold the plates in place.

The invention has for a further object to provide a tie of the character stated wherein the rail plates shall have serrated portions for engagement by serrated portions of rail clamps secured to the plates by bolts, the engagement between the plates and clamps preventing the clamps and consequently the rails from having any inward or outward movement with respect to the tie.

The invention has for a further object to provide a tie of the character stated wherein the rail plates shall be provided in the serrated portions thereof with keyhole slots for the reception of the bolts, the formation of the slots permitting the bolts to be readily applied to the plate after the application of the plate to the tie and also permitting the ready removal of the bolts when occasion requires.

The invention has for a further object to provide a tie of the character stated wherein the reinforcing means shall have portions thereof located directly below the rail plates, and wherein such portions shall be spaced downwardly from the rail plates sufficiently to arrange substantial portions of the tie therebetween, such tie portions insulating the rail plates from the reinforcing means and thus preventing the short circuiting of opposing rails, and such tie portions permitting the formation in the ties of recesses located below the rail plates for the reception of the heads of the bolts and to carry off any water passing through the bolt receiving slots of the rail plates.

With the foregoing and other objects in view, the nature of which will appear as the description proceeds, the invention consists in the construction, combination and arrangement of parts hereinafter fully described and claimed, and illustrated in the accompanying drawings, wherein:—

Figure 1 is a view partly in top plan and partly in horizontal section of a concrete railroad tie embodying my invention.

Figure 2 is a view partly in side elevation and partly in vertical section of the tie.

Figure 3 is a top plan view on an enlarged scale of a fragmentary portion of the tie.

Figure 4 is a sectional view taken on the vertical planes indicated by the line 4—4 of Figure 3.

Figure 5 is a sectional view taken on the vertical planes indicated by the line 5—5 of Figure 4.

Figure 6 is a bottom plan view of one of the rail clamps.

Figure 7 is a plan view of a shim adapted to be applied between the rail plate and rail clamp to accommodate for the heaving of the track in winter.

Figure 8 is a sectional view taken on the horizontal plane indicated by the line 8—8 of Figure 7.

Figure 9 is a view partly in side elevation and partly in vertical section of a fragmentary portion of the tie reinforcing means, and

Figure 10 is a sectional view taken on the vertical plane indicated by the line 10—10 of Figure 9.

Referring in detail to the drawings, 1 designates a concrete railroad tie which, in accordance with my invention, is provided with a reinforcing bar 2 and rail plates 3. The reinforcing bar 2 is completely embedded in and extends longitudinally of the tie 1, and the rail plates 3 are recessed in the upper surfaces of the end portions of the tie. The reinforcing bar 2 comprises a central portion 2a and end portions 2b, the central portion being greater in height than the end portions and located between the rail plates 3, and the end portions being located below and spaced from the rail plates. The

central portion 2a of the reinforcing bar 2 is provided with a longitudinal opening 4 through which a portion of the tie 1 passes. The difference in height between the central portion 2a and the end portions 2b of the reinforcing bar 2, provides at the junctures of these portions shoulders 5 which, together with that portion of the tie 1 passing through the opening 4 of the reinforcing bar, hold the reinforcing bar against endwise displacement with respect to the tie.

The tie 1 is also reinforced by rods 6 which are embedded in and extend longitudinally of the tie at opposite sides of the lower edge 15 portion of the reinforcing bar 2. The rods 6 are of sectional formation, and the sections 6a thereof are provided with angular terminals 7 which serve to hold them against longitudinal movement with respect to the tie 1. The sections 6a of each of the rods 6 are located one in a higher plane than the other and have their inner ends arranged in overlapping relation at the transverse center of the tie 1, the overlapping portions of 25 the rods being connected by couplings 8 of insulating material. Transverse rods 9 are embedded in the tie 1 below the rods 6, and they are provided with angular terminals 10 which serve to hold them against endwise displacement with respect to the tie.

The rail plates 3 are provided at opposite sides of their transverse central or rail receiving portions with anchors 11 which are embedded in the tie 1 at opposite sides of the reinforcing bar 2. Those anchors 11 that are located outwardly of the central portions of the rail plates 3 inclined downwardly and outwardly, those anchors located inwardly of such plate portions incline downwardly and inwardly, and the anchors are provided with anchor lower ends 12, to the end that they may hold the rail plates against accidental inward or outward movements with respect to the tie. The rail plates 3 are provided 35 at opposite sides of their central or rail receiving portions with serrated portions 13, and the plates are provided in such portions with keyhole slots 14 which extend laterally from the rail receiving portions of 40 the plates with their larger ends remote from such plate portions. The tie 1 is provided below the serrated portion 13 of the rail plates 3 with recesses 15 for the reception of 45 the heads of bolts 16.

50 The recesses 15 open out through the vertical sides of the tie 1, and their bottom walls incline downwardly in the direction of such sides to prevent the accumulation therein of any water passing through the slots 14 and the rail plates 3.

55 The rails, one of which is shown in Figures 3-5 and designated 17, are secured to the tie 1 by clamps 18 which contact with the inner and outer base flanges of the rails and which 60 are secured to the rail plates 3 by the bolts 16.

The rail clamps 18 are provided with serrations 19 for engagement with the serrations 13 of the rail plates 3, to the end that there will be established between the rail clamps and rail plates an engagement that will positively hold the rails against inward and outward movements with respect to the tie 1. Shims 20 having corrugated upper and lower sides, are provided in order to accommodate for the heaving of the track in winter and 75 when conditions require their use these shims are positioned upon the bolts 16 between the rail plates 3 and the rail clamps 18.

From the foregoing description, taken in connection with the accompanying drawings, 80 it will be apparent that the reinforcing means, which comprises the bar 2 and the rods 6 and 9, strengthen the concrete tie 1 to such an extent as to practically render the tie indestructible, that the anchors 11 firmly secure the rail plates 3 to the tie and also function to reinforce the end portions of the tie, and that the engagement between the rail clamps 18 and the rail plates is such as to hold the rails against movement with respect to the tie.

It should also be understood that the spacing of the end portions 2b of the reinforcing bar 2 downwardly from the rail plates 3 provides a substantial thickness of the tie material between these bar portions and the plates, that such tie portions insulate the rail plates from the reinforcing means and permit the formation of the recesses 15 without weakening the tie. The rail plate anchors 11 are spaced from the sides of the reinforcing bar 2 to also insulate them from such bar. The T formation of the reinforcing bar 2 renders it especially strong and adapts it to reinforce the tie 1 against injury by forces 100 acting vertically and horizontally against the tie.

While I have described the principle of the invention, together with the structure which I now consider the preferred embodiment thereof, it is to be understood that the structure shown is merely illustrative and that such changes may be made, when desired, as fall within the scope of the invention as 110 claimed.

What is claimed is:—

1. In a concrete railroad tie, a reinforcing bar of T-form in vertical section and embedded in and extending longitudinally of the tie, the web of the bar being provided with a longitudinal opening through which passes a portion of the tie, and the end portions of the bar having their upper sides located in a plane below the upper side of the central portion of the bar to provide shoulders cooperating with the tie portion passing through said opening to hold the bar against endwise movement with respect to the tie.

2. In a concrete railroad tie, a reinforcing bar of T-form in vertical section and em- 120

- bedded in and extending longitudinally of the tie, the web of the bar being provided with a longitudinal opening through which passes a portion of the tie, and the end portions of the bar having their upper sides located in a plane below the upper side of the central portion of the bar to provide shoulders cooperating with the tie portion passing through said opening to hold the bar against endwise movement with respect to the tie, and reinforcing rods embedded in and extending longitudinally of the tie at opposite sides of the rear edge portion of the bar.
3. In a concrete railroad tie, a reinforcing bar of T-form in vertical section and embedded in and extending longitudinally of the tie, the web of the bar being provided with a longitudinal opening through which passes a portion of the tie, and the end portions of the bar having their upper sides located in a plane below the upper side of the central portion of the bar to provide shoulders cooperating with the tie portion passing through said opening to hold the bar against endwise movement with respect to the tie, and reinforcing rods embedded in and extending longitudinally of the tie at opposite sides of the rear edge portion of the bar, the rods being each of sectional formation with their sections located in different horizontal planes and their inner ends arranged in overlapped relation, and an insulating member coupling the overlapped end portions of the sections of each rod.
4. In a concrete railroad tie, a reinforcing bar of T-form in vertical section and embedded in and extending longitudinally of the tie, the web of the bar being provided with a longitudinal opening through which passes a portion of the tie, and the end portions of the bar having their upper sides located in a plane below the upper side of the central portion of the bar to provide shoulders cooperating with the tie portion passing through said opening to hold the bar against endwise movement with respect to the tie, reinforcing rods embedded in and extending longitudinally of the tie at opposite sides of the rear edge portion of the bar, and transverse rods embedded in the tie below the bar and longitudinal rods, the longitudinal and transverse rods having angular terminals holding them against endwise movement with respect to the tie.
5. In a concrete railroad tie, rail plates recessed in the upper side of the tie, and inner and outer anchors secured to the rail plates and embedded in the tie, the outer anchors inclining downwardly and outwardly and provided with angular lower ends, and the inner anchors inclining downwardly and inwardly and provided with angular lower ends.
6. In a concrete railroad tie, a reinforcing bar of T-form in vertical section and having

a central portion of greater height than its end portions, the bar being embedded in and extending longitudinally of the tie, rail plates recessed in the upper side of the tie directly above the end portions of the bar, and anchoring elements secured to the rail plates and embedded in the tie at opposite sides of the end portions of the bar.

7. In a concrete railroad tie, a reinforcing bar of T-form in vertical section and having a central portion of greater height than its end portions, the bar being embedded in and extending longitudinally of the tie, rail plates recessed in the upper side of the tie directly above the end portions of the bar, and anchoring elements secured to the rail plates and embedded in the tie at opposite sides of the end portions of the bar, the rail plates being provided with serrated portions having slots, and the tie being provided below such portions of the rail plates with recesses having bottom walls inclining downwardly in the direction of the vertical sides of the tie.

8. In a concrete railroad tie, a reinforcing bar of T-form in vertical section and embedded in and extending longitudinally of the tie, the web of the bar being provided with a longitudinal opening through which passes a portion of the tie, and the end portions of the bar having their upper sides located in a plane below the upper side of the central portion of the bar to provide shoulders cooperating with the tie portion passing through said opening to hold the bar against endwise movement with respect to the tie, reinforcing rods embedded in and extending longitudinally of the tie at opposite sides of the rear edge portion of the bar, transverse rods embedded in the tie below the bar and longitudinal rods, the longitudinal and transverse rods having angular terminals holding them against endwise movement with respect to the tie, the rail plates recessed in the upper side of the tie, and anchors secured to the rail plates and embedded in the tie and provided with angular lower ends.

In testimony whereof I hereunto affix my signature.

ROBERT N. SCHUMANN.
